United States Patent Office.

JOHN H. BELLAMY, OF CHARLESTOWN, MASSACHUSETTS, ASSIGNOR TO SAMUEL D. NILES AND BENJAMIN A. WARD.

Design No. 4,465, dated November 15, 1870.

DESIGN FOR A BRACKET.

The Schedule referred to in these Letters Patent and making part of the same.

To all whom it may concern:

Be it known that I, JOHN H. BELLAMY, of the city of Charlestown, county of Middlesex and State of Massachusetts, have originated and designed a new and useful Pattern for Bracket, of which the following is a full, clear, and exact description, reference being had to the accompanying photographs making a part of this specification.

The nature of my design consists of emblems so arranged and constructed as to show above the shelf A, pillars on each side B B, surmounted by chapters C C, and globes D D, at the top of which, and connected with the globes or pillars, is a square, 3, compass F, inclosing the letter G.

Below the square is a level, H, gavel I, and rule J, under which is an hour-glass with wings K, the wings

supporting on the right a ladder, L, and on the left two parallels M M, inside of which is a book, N, and circle O.

Below the shelf A is a trowel, R, on the right of which is a square, S, on the left a plumb, T, the three encircled in ornamental scroll-work.

The shelf is supported by a square, V, and an ornamental letter, G-W.

What I claim as my invention, and desire to secure by Letters Patent, is—

The design for a bracket herein set forth.

JOHN H. BELLAMY.
